DESIGN FOR A COMBINED JAR CAP AND ASHTRAY TOP

Theodore Sneddon and Stanley Safranski, Chicago, Ill., assignors to The Aridor Company, Chicago, Ill., a corporation of Illinois

Application February 26, 1936, Serial No. 61,364

Term of patent 7 years

To all whom it may concern:

Be it known that we, Theodore Sneddon and Stanley Safranski, citizens of the United States, residing in Chicago, Cook County, Illinois, have invented a new, original, and ornamental Design for a Combined Jar Cap and Ashtray Top, of which the following is a specification, reference being had to the accompanying drawing forming a part thereof.

We claim:

The ornamental design for a combined jar cap and ashtray top, substantially as shown and described.

THEODORE SNEDDON.
STANLEY SAFRANSKI.
